J. A. GASTEIGER,
PNEUMATIC CONVEYER,
APPLICATION FILED JAN. 7, 1920.

Patented May 23, 1922.

FIG. 1

FIG. 2

FIG. 3

INVENTOR

*Justus A. Gasteiger
By Kay a Totten,
Attorneys*

UNITED STATES PATENT OFFICE.

JUSTUS A. GASTEIGER, OF DORMONT, PENNSYLVANIA.

PNEUMATIC CONVEYER.

1,417,052.

Specification of Letters Patent. Patented May 23, 1922.

Application filed January 7, 1920. Serial No. 349,942.

To all whom it may concern:

Be it known that I, JUSTUS A. GASTEIGER, a citizen of the United States, and resident of Dormont, in the county of Allegheny 5 and State of Pennsylvania, have invented a new and useful Improvement in Pneumatic Conveyers; and I do hereby declare the following to be a full, clear, and exact description thereof.

10 My invention relates to a pneumatic conveyer.

The object of my invention is to provide a pneumatic conveyer for the conveying of grain, earth, sand, lime, loose cement or 15 other materials in which the material itself is employed as a seal to maintain the vacuum in the receiving chamber, the discharge from the receiving chamber being so controlled as to maintain this seal continuously during 20 the operation of the conveyer.

To these ends my invention comprises the novel features hereinafter set forth and claimed.

In the accompanying drawing, Fig. 1 is 25 a vertical sectional elevation; Fig. 2 is a plan view of my improved pneumatic conveyer; and Fig. 3 is a cross section on the line 3—3, Fig. 1.

While I have illustrated my invention in 30 connection with a portable pneumatic conveyer, it will be understood that I do not limit myself in any sense to this particular type.

The numeral 2 designates a suitable receptacle which is supported by the legs 3 which may be formed of angle-bars secured to the sides of said receptacle. The receptacle 2 has the inlet 4 to which the suction pipe 5 is connected, said pipe having 35 at its lower end a suitable nozzle 6. The shape and size of this nozzle 6 may vary 40 according to the material to be conveyed.

The receptacle 2 is preferably made in the form of a hopper with the inclined bottom sheets 7, with the opening 8 communicating with the sealing chamber 9 which is riveted or otherwise secured to the inclined wall 7 of the receptacle 2.

The sealing chamber 9 is normally closed 50 by the valve or gate 10 which is adapted to swing on the hinge rod 11 and engaging the lugs 12 on the sealing chamber 9. A spring 13 surrounds the hinge rod 11 and engages 55 the gate 10 to hold the same normally closed.

A shaft 14 is journaled in suitable bear-

ings 15 on the top 16 of the receptacle 2, said shaft carrying at its lower end the spiral conveyer 17 which is adapted to enter and fit within the sealing chamber 9.

The upper end of the shaft 14 carries the 60 worm wheel 18 which is driven by the worm 18^a on the shaft 19. The worm shaft 19 has the pulley wheel 20 which is connected up by the belt 21 with the pulley wheel 22 on the motor shaft 23 of the motor 24. The 65 fan 25 is driven by the motor shaft 23, said fan being of any suitable construction, and a pipe 26 is connected up to said fan and to the receptacle 2 whereby a vacuum or partial vacuum may be maintained in said 70 receptacle.

Baffle plates 27 are arranged within the receptacle 2 to baffle the material which enters said receptacle by the pipe 5 and prevent its escape to the pipe 26, said baffles 75 acting to direct the material down toward the outlet 8 of said receptacle.

For the purpose of suspending the apparatus from a grain or other handling device, the chains 28 may be employed connected up to a ring 29.

When my pneumatic conveyer is in operation, the motor is started and by means of the fan 25 a partial vacuum is created in the receptacle 2 which, through the suction 85 pipe 5 acts to draw the material to be conveyed into the nozzle 6 to be delivered by the pipe 5 into the receptacle 2. Material on entering said receptacle is directed downwardly by the baffles 27 and accumulates in 90 the sealing chamber 9 as well as in the receptacle 2. The spiral conveyer 17 acts to force or drive the material down through the sealing chamber 9 and the force imparted to the material by said spiral conveyer overcomes the action of the spring 13 and the gate or valve 10 is opened whereby the material is delivered from the sealing chamber 95 9.

The resistance offered by the spring 13 acts to prevent the discharge of the material in such quantity as to destroy the seal created by the material which fills the sealing chamber 9 at all times and prevents the destruction of the vacuum in the receptacle 2, so that the suction of the material 100 by the pipe 5 continues without interruption and the apparatus works in a continuous manner, always discharging a uniform amount from the receptacle 2.

The full effect of the fan is obtained at 110

all times so that there is no waste of power and there is a consequent economy in operation.

What I claim is:

- 5 In a pneumatic conveyer, the combination of a suitable receptacle, means for maintaining suction in said receptacle, downwardly extending baffles in said receptacle, a sealing chamber disposed below said receptacle forming a discharge outlet for same, a vertically arranged spiral conveyer in
- 10

said sealing chamber and forming a close fit therewith, means for driving said spiral conveyer, and a spring-actuated valve controlling the discharge outlet of said sealing chamber.

In testimony whereof, I, the said JUSTUS A. GÄSTEIGER, have hereunto set my hand.

JUSTUS A. GÄSTEIGER.

Witnesses:

A. E. CLANEY,
ROBT. D. TOTTEN.
